UNITED STATES PATENT OFFICE.

THOMAS E. KEARNS, OF NEW KENSINGTON, PENNSYLVANIA, ASSIGNOR OF
ONE-HALF TO HENRY M. GABEL, OF CINCINNATI, OHIO.

WHITE-LEAD DRIER.

SPECIFICATION forming part of Letters Patent No. 693,869, dated February 25, 1902.

Application filed October 14, 1901. Serial No. 78,528. (No model.)

To all whom it may concern:

Be it known that I, THOMAS E. KEARNS, a citizen of the United States, residing at New Kensington, Westmoreland county, Pennsylvania, (post-office address New Kensington, Pennsylvania,) have invented certain new and useful Improvements in White-Lead Driers, of which the following is a specification.

This invention, pertaining to white-lead driers of the pan type, will be readily understood from the following description, taken in connection with the accompanying drawings, in which—

Figure 1 is a side elevation of my improved drier; Fig. 2, a vertical transverse section; Fig. 3, a plan; and Fig. 4 a partial vertical transverse section on an enlarged scale.

In the drawings, 1 indicates columns arranged in pairs opposite each other at a distance corresponding with the width of the drying-pans and forming two longitudinal series; 2, brackets projecting inwardly from the columns; 3, I-beams secured to these brackets and extending across the general structure, whereby the two columns of each pair become united, the number of these beams in each vertical series corresponding with the number of pans—three in the illustration; 4, steam-pipes disposed longitudinally of the general structure and resting on the I-beams and forming, in effect, a strong slatted floor over each horizontal series of beams; 5, returns at the ends of the pipes, forming each horizontal series of pipes into a continuous conduit; 6, steam-inlet formed by the initial end of each of the horizontal series of connected pipes, the same being adapted for connection with any suitable source of controlled steam-supply; 7, steam-outlets formed by the terminal end of each of the horizontal series of connected pipes, the same being adapted for connection with any suitable provision for disposing of the water of condensation, preferably a steam-trap; 8, the pans, formed of sheet-copper, rectangular in plan and having a width adapted to fit between the columns and a length adapted to the entire series of columns, the bottoms of these pans resting on the pipes; 9, a stiffening-bar around

the rim of each pan, the metal of the rim of 50 the pan being turned around this bar, and 10 clamps secured against the inner faces of the columns over the rims of the pans and engaging within the rims, so as to retain the rims against the columns.

In practice I am making the pans thirty-five feet long and ten feet wide and nine inches deep and arranging them in vertical series of three, as indicated in the drawings, the I-beams being six inches deep and the steam-pipes two inches in size. The clamps 10 throughout the general structure do not pinch the rims of the pans, but leave them free to slide as expansion and contraction take place; but at the central pair of columns the clamps 60 are to be tightened up so as to pinch the rims of the pans and prevent their movement relative to that particular pair of columns, the longitudinal movement of the pans relative to the columns taking place at each side of 70 these central columns. The heat from the supporting steam-pipes evaporates the moisture from the material in the pan immediately upon the pipes, and the vapors rise to the pipes above and pass out sidewise, the dissipation of the vapor being extremely rapid, resulting in high efficiency of the apparatus, which, as compared with the usual structures, brings about marked economy in time and steam.

80 I claim as my invention—

In a white-lead drier, the combination, substantially as set forth, of two longitudinal series of columns, a pan extending longitudinally between said two series of columns and 85 having its side rims connected with the inner faces of said columns, beams extending across from one series of columns to another and connecting the columns in pairs and disposed below the pan, and steam-pipes arranged parallel with each other and with the series of columns disposed upon the beams and directly supporting the bottom of the pan.

90 THOMAS E. KEARNS.
